UNITED STATES PATENT OFFICE.

CHARLES H. WILD, OF BALTIMORE, MARYLAND, ASSIGNOR TO BURT MACHINE COMPANY, INCORPORATED, A CORPORATION OF MARYLAND.

CAN-LABELING MACHINE.

Application filed July 2, 1921. Serial No. 482,038.

To all whom it may concern:

Be it known that I, CHARLES H. WILD, a citizen of the United States of America, residing in the city of Baltimore, State of Maryland, have invented certain new and useful Improvements in Can-Labeling Machines, of which the following is a specification.

The invention relates particularly to the application of labels to cans having protruding portions in the cylindrical sides or bodies most frequently appearing in the form of bale ears or eyes for the attachment of the bales or handles to the cans.

The machine shown is similar in structure to previously patented machines, the machine of United States Patent No. 1,323,940 being a good illustration of this type. The difficulties incident to the attachment of labels to cans having protruding ears without special provisions to this end are apparent and the improvements employed in the present machine as distinguished from the previous can labeling machines referred to relate to the provision of means for overcoming these difficulties which may be listed as bumping and sliding of the cans, uncertain and uneven progress of the cans through the machine, the difficulty incident to causing the openings in the labels to register with the ears and that incident to laying the labels flat on the can surfaces.

To overcome these difficulties I have provided the ways or floor of the machine on which the cans roll, with spaced openings to admit the ears as the cans roll through the machine so that contact of the cylindrical surfaces of the cans with the floor or ways is regular and uniform and the cans roll without bumping or sticking.

I have also provided for so starting or for so positioning the cans at the start, that the ears do in fact engage the openings provided for this purpose the same being arranged to provide for different sized cans.

In addition to the aperturing of the floor or ways, the label support or table is apertured and the tension rolls are cut away opposite the ears eliminating all chances of sticking or catching of the can on account of the ears as it passes through the labeling machine.

In the accompanying drawing I have illustrated a labeling machine of the type referred to adapted to the labeling of cans hav-

ing bale ears or similar projections, the disclosure being the preferred embodiment of my invention which is the subject of this application.

In the drawings Figure 1 is a side elevation of the machine;

Figure 2 is a plan of the same;

Figure 3 is an enlarged detail showing the position of a can with an ear in contact with the gauge in position for starting;

Figure 4 is a plan of a label apertured for use on a bale can.

Referring to the drawings by numerals, the machine as shown includes a horizontal frame 1, which may consist of two horizontal bars suitably supported; side guides 2, which are parallel to and spaced above the frame serving to prevent lateral displacement of the cans as they roll through the machine and a can actuating belt 3, which is driven by a pulley 4, at one end and supported on a suitable idler pulley 5 at the other end. This belt is horizontal, parallel to the frame and spaced above the frame, the lower span of the belt serving to contact the cans from above and roll them through the machine.

The cans enter the machine by way of an inclined chute 7 at the left in Figure 1, pass through the machine propelled by the belt 3 and leave the machine by the inclined chute 8. The belt is held in contact with the cans by means of spring pressed rollers 10 as illustrated and described in the previous patent referred to.

Adhesive, preferably cement, is applied to the cans as they pass, the cement being held in a pot or receptacle 12, from which it is raised by a roller or brush not illustrated, the same being carried on shaft 13, driven by belts and pulleys 14—15 and 16 from the pulley 5 which carries the can actuating belt.

The chute 7 which may be fed by hand has a passage or entrance 9, for the cans at right angles to the direction of the chute. The cans are inserted in this entrance with their cylindrical walls or sides parallel to the walls or sides of the entrance passage and moved or slid in the direction of their axes until they reach the main passage or chute 7. At this point each can is rotated backwards, i. e., left handed as viewed in Figure 1, until one of the bale ears comes in contact with the starting gage or stop 110

17, which is secured to the end wall 18 of the chute.

This may be adjustable as shown particularly in Figures 1 and 3, the gage preferably consisting of a slotted upright 19, secured to the end wall 18, of the chute by a screw 20, set in the end wall and passing through the vertical slot 21, in the upright 19. An arm 22, at the upper end of said upright turned at right angles carries the gage proper. A screw 24 seated in said arm passes through a slot 25, in the gage proper, the same being in the form of a sliding plate 26. The latter is adjustable in the direction of the feed of the machine providing for the variation in spacing of the ears on the different sizes of cans.

The chute 7 is preferably slotted at 27 directly beneath the gage to receive the lower ear and at a point further along as indicated by reference character 28 to receive the upper ear as it comes around. The chutes may be made interchangeable to provide for variation of the cans but variation is also provided for the adjustability of the gage up and down by means of slot 21, and thumb screw 20, and in the direction of the feed by means of slot 25 and thumb screw 23, and by a multiple spacing of the openings or slots as hereinafter appears.

As the cans leave the chute and enter the ways beneath the first pulley 5, they pass over the cement pot 12 where heat liquefied cement is applied as is common in machines of this class. Beyond this cement pot the support 30 is apertured at 31 to admit the corresponding ear and retain the spacing of the cans so that the ears will register with the apertures in the label on reaching the label table. The latter is substantially centrally placed in the machine and is indicated by reference character 32. The label table is actuated in any manner to maintain a suitable feed of the labels as illustrated in the previous patents on this subject, the important feature of the label table of the present machine being that it is apertured at 33 and 34 to admit the ears, the tables being interchangeable to provide for the various shape and sizes of cans, length of labels and spacing of the ears. The labels are placed on the table with the apertures registering. They are supplied to the table in packs as in other labeling machines.

Beyond the table 32 is the presser plate 36, the same being slotted, i. e., provided with elongated openings 37 spaced to admit the bale ears on the cans. The elongation of the openings provides for some variation of diameter and of the spacing of the ears though the plate is interchangeable providing for any spacing of the openings and of the ears and variation in the size of the cans.

Beyond the presser plate 36 is a pad or sponge 38. The plate 36 is a spring plate

corresponding to the plate 49, in the United States Patent #1,323,940, to John L. Whitehurst and Charles H. Wild. It differs therefrom principally as to slots 37. The plate serves to press each label against the can surface immediately after it is taken up by the can.

It will be noted that the openings to receive the bale ears are on the near side of the machine as viewed in Figure 2 which presupposes that the cans are to be inserted in the machine top first. This is, of course, a matter of choice of design of the machine determined by convenience in construction and operation.

The spacing between the openings 27 and 31 may be changed by changing the chute but is ordinarily chosen as two circumferences of the large size standard cans handled and three circumferences of the small standard cans handled or it may be a convenient multiple. It will also be noted that the tension or presser rollers 10 are cut away to the shaft or reduced in diameter at points 35 in alignment with the apertures making it unnecessary to consider the position of these rollers in gaging the starting point of the cans and that paste is applied to the ends of the labels on the label table by means of a transverse belt 40, passing through a paste pot 41 and carried on pulleys 42, 43 and 44, the latter being carried on a drive shaft 45, actuated by bevel gear 46, driven by a second bevel 47, which is in turn driven by a grooved pulley 48, which is driven by belt 49, passing over pulley 50 on the transverse shaft 51, which carries the actuating belt driving pulleys 4.

The labels are applied in the usual manner by rolling them around the cans and lapsing the coated edge. With the help of the starting gage which gives uniform placing of the bale ears relatively to the ways, the bale ears are caused to enter the openings in the supports and presser plates and to register with the holes in the labels, giving a uniform progress of the cans avoiding bumping, slipping and sticking or jamming, resulting in uniform rolling and pressing of the labels on the cans, giving the product, i. e., the labeled can, neatness and permanence as to the retention of the label.

The operation of the machine is believed to have been fully set forth in connection with the description of the machine. Having thus described specifically and in detail a single embodiment of my invention, I would have it understood that the specific terms herein are used descriptively rather than in a limiting sense, the scope of the invention being defined in the claims.

What I claim and desire to secure by Letters Patent is:

1. In a can labeling machine for affixing labels to cans means for feeding the cans

through the machine; a support for the cans as they pass through the machine and suitable means for applying adhesive to the cans and label holding and feeding means and 5 means for sticking the ends of the labels, the support having spaced apertures to receive the ears as the cans roll through the machine, providing uniformity of contact of the cans with the support and means for 10 causing the bail ears to register with the apertures.

2. In a can labeling machine for affixing labels to cans means for feeding the cans through the machine; label supporting feed- 15 ing and pasting means, a support for the cans as they pass through the machine and suitable adhesive applying means for the cans, the supports having suitably spaced apertures to receive the ears as the cans roll 20 through the machine, providing uniformity of contact of the cans with the support and permitting them to roll through the machine uniformly without slipping or sticking, and tension rollers apertured to pass the ears and 25 a starting gage to cause the bail ears to register with the apertures.

3. In a can labeling machine for labeling of cans having ears, a chute for feeding cans to the machine, having an entrance 30 opening at the side, a gage for positioning the ears in alignment with the opening, the chute being provided with suitably spaced apertures for the ears, some of said apertures being elongated, ways, means for applying 35 adhesive to the cans and a horizontal belt for propelling the cans along the ways, the ways including suitable supporting means for the cans, apertured to admit the ears, a label table having apertures spaced to correspond 40 to the ears, pasting means for sticking the ends of the labels and a presser plate having correspondingly spaced apertures.

4. In a can labeling machine for treatment of cans having ears, a chute for feeding cans to the machine, a gage for positioning 45 the ears in alignment with the opening, the chute being provided with suitably spaced apertures for the ears, said apertures being elongated, ways, means for applying adhesive, and a horizontal belt for propelling the 50 cans along the ways, the ways including suitable supporting means for the cans apertured to admit the ears, a label table having apertures spaced to correspond to the ears and a presser plate having correspondingly 55 spaced apertures.

5. In a can labeling machine for treatment of cans having ears, a chute for feeding cans to the machine, having an entrance opening at the side, a gage for positioning the ears 60 in alignment with the opening, the chute being provided with suitably spaced apertures for the ears, said apertures being elongated, ways, means for applying adhesive, and a horizontal belt for propelling the cans along 65 the ways, the ways including suitable supporting means for the cans apertured to admit the ears, a label table having apertures spaced to correspond to the ears and a presser plate having correspondingly spaced 70 apertures, also apertured to receive the cans.

6. In a machine for labeling cans with bail ears, ways, means for applying adhesive, means for propelling the cans along the ways, the ways having apertures to admit the ears, and a starting gage to cause the cans to register with the apertures. 75

Signed by me at Baltimore, Maryland, this 29th day of June, 1921.

CHARLES H. WILD.
